ATTORNEYS.

UNITED STATES PATENT OFFICE.

ELSA A. CAZIARC, OF FORT SHERIDAN, ILLINOIS.

SEMAPHORE TOY.

1,347,682.

Specification of Letters Patent.

Patented July 27, 1920.

Application filed July 11, 1918. Serial No. 244,454.

To all whom it may concern:

Be it known that I, ELSA A. CAZIARC, a citizen of the United States, residing at Fort Sheridan, county of Lake, State of Illinois, have invented a certain new and useful Improvement in Semaphore Toys, and declare the following to be a full, clear, and exact description of the same, such as will enable others skilled in the art to which it pertains to make and use the same, reference being had to the accompanying drawings, which form a part of this specification.

My invention has for its object to produce a simple and attractive toy in the form of a soldier or other person provided with signal flags which may be readily manipulated in accordance with the practice of two-arm semaphore signaling.

The various features of novelty whereby my invention is characterized will herein-after be pointed out with particularity in the claims; but, for a full understanding of my invention and of its objects and advantages, reference may be had to the following detailed description taken in connection with the accompanying drawing, wherein:

Figure 1 is a front view of a device arranged in accordance with a preferred form of my invention;

Fig. 2 is a front view, on an enlarged scale, of the rear half of the device, the front half being removed;

Fig. 3 is a section taken approximately on line 3—3 of Fig. 2; and

Fig. 4 is a side or edge view of the lower or base portion of the device.

Referring to the drawing, 1 and 2 represent two slabs or thick sheets which may conveniently be in the form of thin boards, cut so as to conform to the outline of an armless soldier as viewed either from the front or the rear. The members 1 and 2 are secured together back to back and the resulting compound member may be decorated on opposite sides in imitation of a uniformed soldier. Rigid extended arms, 3 and 4, are joined to the body member so as to permit the arms to be swung in front of the figure. Each arm terminates in a hand holding a signal flag, 5, which is preferably made of stiff material so that it will not flap about when the arms are quickly moved. The arms are preferably spring controlled so that they always bend to assume a neutral position as, for example, a

position shown in dotted lines in Fig. 1 and cords or cables, 6 and 7, are provided for manipulating the arms against the tension of the springs.

In the arrangement shown, each arm is fixed on the outer end of a long cylindrical hub, 8, projecting through the front member 1 of the figure from a drum or reel, 9, housed within a suitable pocket, 10, between the members 1 and 2. On each of the drums, 9, is wound one of the cables which in turn passes down through a suitable passageway or tunnel, 11, of which there are two each extending from the vicinity of one of the drums to the corresponding foot or ankle of the figure. At the lower end of each passage or tunnel are two guides, preferably in the form of pulleys, 12 and 13. The passages or tunnels communicate with the outside at the front of the figure through holes, 14, behind which the pulleys, 12, lie. Similarly holes, 15, in the back member of the figure place the lower ends of the passages 11 in communication with the outside on the rear side of the figure; the pulleys, 13, lying opposite or in the opening 15. With this arrangement the cables may be passed out at the base of the figure so as to permit the arms to be manipulated while the soldier is being faced, or the cables may be passed out through the rear of the figure so as to permit the manipulator to be positioned behind the soldier while signaling.

At the bottom of the device there may be a comparatively broad, flat base, 16, on which the device may be held upright and, when signaling, the member 16 may be clamped to a table or other supporting member.

The springs for returning the arms to what may be called zero positions may conveniently be housed in the drums on whose hubs the arms are fastened. In the arrangement shown, there are fastened in the back member or plate of the figure two studs, 17, each of which is co-axial with one of the drums and preferably has a part or journal, 18, fitting into a suitable bearing in the corresponding drum and its hub. Each stud 105 has a plate, 19, which fits into the open side of the corresponding cable drum and forms therewith an inclosed chamber or spring casing. In each chamber or spring casing is an ordinary spiral clock spring, 20, fastened at its end to the stud and at its outer end to the drum. By securing the studs

rigidly to the back plates of the figure and providing them with extensions or journals which project into the hubs of the rotatable drums, good supporting bearings are provided for the swinging arms and accurate alinement will be maintained in a manner that would not be possible if the journal bearings for the members 8 were in the wood or other unsuitable material instead of being metal to metal bearings.

The parts are so proportioned and coördinated that normally the arms take the positions shown in dotted lines in Fig. 1. For the purpose of signaling, the cables are passed out through the front or through the back, depending upon whether the person giving the signals is to be behind or in front of the soldier; and the cords or cables are then grasped one in each hand so that each arm may be moved at will independently of the other.

I claim:

1. A device of the character described, comprising a figure having flag-carrying arms hinged to swing in imitation of a person signaling in accordance with the two-arm semaphore system, springs tending to move the arms in one direction, two sets of pulleys near the bottom of said figure arranged in pairs, one at the rear and the other at the front of the figure, and a cable extending from each arm down through said figure in position to permit it to be passed

over either of the pulleys of the corresponding pair and thus permit the arms to be manipulated either from the front side of the figure or from in rear of the figure.

2. In a device of the character described, a figure made of two members laid back to back, sockets arranged between said members, spring drums arranged within said sockets, each drum having an elongated hub projecting axially therefrom to the front side of one of said members, arms attached to the free ends of said hubs, and cables passing over said drums and adapted to rotate them in opposition to the springs contained therein.

3. In a device of the character described, a figure made of two members laid back to back, sockets arranged between said members, spring drums arranged within said sockets, each drum having an elongated hub projecting axially therefrom to the front side of one of said members, arms attached to the free ends of said hubs, pulleys near the bottom of said figure, and cables wound on said drums and passing downwardly over said pulleys, the free ends of the cables projecting beyond said figure so as to permit them to be grasped for the purpose of operating said arms.

In testimony whereof, I sign this specification.

ELSA A. CAZIARC.
